HOLDING DEVICE FOR CAP COVERS OR TOPS

Ulrich E. Biaesch, Philadelphia, Pa.

Application November 23, 1937, Serial No. 176,090

4 Claims. (Cl. 2—195)

The invention relates to headwear having a lower frame comprising a sweatband and a support for any suitable cover or top.

The main purpose of the invention is to hold 5 a top or cover on a lower cap frame by a substantially in-elastic top or cover welt fitting over a resilient band approximating in girth the circumference of the head.

A further purpose is to support a removable 10 cover or top for a cap independently of a stiff cap frame.

A further purpose is to support a cap cover from a resilient flange carried by a soft cap band.

Further purposes will appear in the specification 15 and in the claims.

I have preferred to illustrate the invention by a few constructions only among the many constructions in which it may appear.

Figure 1 is a sectional elevation of a cap having a stiff cap frame.

Figure 2 is an enlarged section of a portion of the cap frame similar to that of Figure 1, but differing slightly from it.

Figure 3 is an inverted perspective view of a removable cap top or cover.

Figure 4 is a section corresponding to Figure 1 but showing a structure lacking an inner stiff band or frame.

Figure 5 is an enlarged fragmentary section 30 corresponding generally to Figure 2 but lacking the top or cover.

Figure 6 is an enlarged section of a portion of Figure 5.

Caps of the type known as "uniform" caps are 35 generally based upon a more or less rigid cap form or frame including an annular so-called inner stiff or rigid band 10 to which the sweatband 11 and outer decorative facing band 12 are usually attached. The cap cover or top is mounted 40 upon the inner band of the frame. Since this inner band is very generally of pulpboard or other material which is readily injured by moisture, the fastening of the cover to the inner band is correspondingly defective and uncertain. It is 45 the present intention to mount the cover upon the outer decorative facing band independent of any stiff inner band. The stiff inner band can then be used or not as preferred. The finish and cap rigidity given by the inner band can be secured if desired and the sweatband and outer facing can then be fastened to the inner band or not as preferred. When the inner band is 50 omitted a very soft effect can be secured, permitting the cap to be put in the pocket without difficulty and at the same time excellent union of

the lower cap structure and cover or top may be attained. In Figures 1 and 2 a stiff frame is shown.

The inner band 10 is usually provided with inner and outer facings 13 and 13' which, when used, will be considered here as with the pulp board merely forming the inner band. In principle their absence or presence does not affect the purpose or function of the inner band. The upper part 14 of the outer and decorative band 15 10 is preferably independent of the inner band. Very commonly a visor 16 is added about which frequently is thrown a strap 17. The lower edge of the outer part of the cap is frequently decorated by a welt 18, here made from the outer 15 band material.

In Figure 1 the sweatband, inner band and outer band are sewed together at 19. In Figure 2 the construction differs from Figure 1 in that the outer band and sweatband provide a pocket 20 within which the inner band is located without being fastened to either the outer band or to the sweatband. In the illustration this is provided by turning the outer band upwardly at 21 to give space between this upturned portion and 20 the rest of the band for the pocket and fastening the sweatband to the outer band at some convenient point, here shown as at 22 close to the turn in the outer band.

In this illustration the outer facing material 30 of the inner band is fastened to the inner band at 23 and the inner facing is fastened to the inner band at 24 at which point the inner facing for the inner band is turned upwardly terminating at 25.

A resilient ring 26 is provided near the upper edge of the frame and very desirably independent of the inner band so that it can function independently of injury to or destruction of the inner band. This resilient ring is shown in Figures 1, 2, 4 and 5 as mounted within the upper edge 27 of the outer band which is most desirably free from attachment to the inner band at this point, though, where an inner band is used, the outer band may be attached to the inner band 45 as in Figure 1.

The resilient ring is shown in enlarged section in Figure 6 as of spring wire which preferably is flattened at the inside at 28 and at the outside at 29 so as to leave a considerable body of 50 wire but to yield first and most easily in radial directions permitting the ring of wire as a ring to be collapsed at one or more parts so as to reduce the effective perimeter about which the welt 30 of the cover is to be passed.

The resilient ring 26 is shown as lying within the folded back portion 31 of the outer band and as but little exceeding in perimeter the adjoining part of the head within the cap, with the purpose and effect that no special type of cap cover or cap top need be used; the cover or top merely needing a welt to limit the perimeter which can be passed over the resilient ring when the latter has been collapsed and which will be held against retraction over the ring when the resilient ring 10 has been allowed to expand to its full size.

Any suitable cover or top 32 thus completes the cap. It is held quite firmly against removal because the welt 30 will not yield to the pull which a normal top or cover receives and will therefore not pass over the covered ring 26 in normal use. The resilient ring must be collapsed to reduce the effective "diameter" before the welt of the top or cover may readily be removed from it. For the present purpose, of determining the circumference over which the welt must be passed, the covering material is considered as part of the "ring".

The construction as described permits any type of crown to be used whether it be soft and flexible or relatively firm and rigid, or any intermediate type of crown between these, the effective requirement being that it has a substantially inextensible lower and inner welt or edge peripherically smaller than the resilient ring.

This way in which the top or cover is secured removably over a resilient ring supported independently of the stiff cap frame distinguishes sharply from such methods of fastening as by snap fasteners engaging with a rigid frame part or retracting cover welts stretching to fit over a device by which they are ultimately held. Where the top or cover can be stretched to allow it to be placed, it can be stretched also for removal and this means that it can be pulled free from the cap frame.

In Figures 4 and 5 the so-called inner band is omitted altogether permitting the use of a soft outer band fitting with a sweat band to form a very soft and non-rigid cap frame. Here again the resilient ring is not much larger in circumference than the size of the head within it.

Where the stiff inner band is not used, the sweat band may provide the only stiffening for the cap frame, permitting the use of very soft and flexible materials for the outer band. This furthermore permits the sagging of the outer band and cover so as to give a very low and rakish cap effect.

With either form of the invention the resilient ring is collapsed to permit the welt of a cover or top to pass over the ring after which the ring is allowed to expand and then holds the welt against accidental removal over it.

It will be evident that the resilient or spring ring supported by the outer band will be effective even where it lies against the inner band in normal use since it will be independent of the inner band, in case of injury to or destruction of the latter, and will continue to function whether the inner band remain in good condition or not.

The invention has been described as applying to caps of the uniform type because the greatest need of substitution of different tops or covers lies in this art. However, it will be evident that the invention is applicable also to caps of civilian type, such for example as golf types. With the form of Figures 1 and 2 this means merely that the stiff frame is not carried up as high as is the stiff frame used for caps of the uniform type. The form of Figures 4 and 5 is particularly well suited to be used in civilian caps.

It will be evident also that a cap suited to use with or without a visor may be used with an eye shade merely whether this be considered to be a visor or to differ therefrom.

In view of my invention and disclosure variations and modifications to meet individual whim or particular need will doubtless become evident to others skilled in the art, to obtain part or all of the benefits of my invention without copying the structure shown, and I therefore, claim all such in so far as they fall within the reasonable spirit and scope of my invention.

Having thus described my invention what I claim as new and desire to secure by Letters Patent is:

1. In a cap having the usual sweatband, an outer flexible facing band and a resilient metal ring mounted directly upon the facing band near the upper end of the band, whereby a removable cover having an inner welt edge substantially in extensible and of smaller effective size than that of the metal ring can be connected with the outer facing band.

2. A cap comprising a stiff cap body, a flexible decorative band located about the body and an inwardly resilient metal ring forming a flange for and attached to the upper edge of the decorative band, close to and outside of the stiff body, whereby through said ring a removable cover 40 may be mounted upon the decorative band as distinguished from mounting the cover upon the cap body.

3. A cap comprising a stiff cap body, a flexible decorative band located about the body secured to the stiff body at its lower edge and free therefrom at its upper edge and an inwardly resilient metal ring forming a flange for and attached to the upper edge of the decorative band, close to and outside of the stiff body, whereby a removable cover having a cover welt of smaller size than the size of the flange may be mounted upon the decorative band.

4. A cap having a stiff inner band, a sweatband and an outer decorative flexible band free from the inner band at its upper edge and a spring wire flange encircling the upper end of the stiff band close to said band and secured to the flexible band as distinguished from being secured to the inner band, whereby a cover for the cap having a substantially inextensible inner welt edge of smaller size than the size of the spring flange can be attached to the decorative band below the spring flange.
